WILLIAM FADER, JOE SCHATMAN, AND LOUIS GOLDBERG, OF NEWARK, NEW JERSEY.

COVER FOR WASHTUBS AND THE LIKE.

1,307,438.

Specification of Letters Patent. Patented June 24, 1919.

Application filed March 19, 1919. Serial No. 283,630.

To all whom it may concern:

Be it known that we, WILLIAM FADER, JOE SCHATMAN, and LOUIS GOLDBERG, citizens of the United States, and residents of Newark, county of Essex, and State of New Jersey, have invented certain new and useful Improvements in Covers for Washtubs and the like, of which the following is a specification.

10 This invention relates to an improved cover and is designed to provide a cover that is made of sheet metal which is usually placed over a frame. This class of cover is usually applied to washtubs and the like and 15 lends itself to enameling or other finishing, but is designed, in the cheaper forms of covers, to be without any coating.

The construction of the cover is such that when the sheet metal is placed around a 20 frame, which is usually of wood, it is held in place and fastened, this being done without driving nails through the cover into the frame, and the seams, which it is not necessary to solder, are tight and are not calculated to receive and hold any grease or dirt 25 and do not permit the entrance of an appreciable amount of water.

It very often happens, with covers of this kind, that they are used as tables or similar 30 supporting surfaces in apartments where economy of room is essential, and the top of the tub does duty as a cover and also as a working surface.

When the cover is closed, any water or 35 liquids that flow on the top, accidentally or otherwise, do not enter the seams because the seams are turned downwardly and the corner seams are closed and the liquid runs off the cover without penetrating into the frame 40 to cause rotting, and in the same way the accumulation of dirt or grease is minimized.

Another object of the invention is to provide a cover of this kind, the manufacture of which is economical, and they can be 45 quickly manufactured after the blanks are cut, these blanks forming the top and bottom members and being suitably joined around the frame to make a symmetrical, substantially smooth cover without projections that are adapted to tear or catch on clothing or the like, and is substantially strong and durable.

The invention is illustrated in the accompanying drawing, in which Figure 1 is a 50 face view of a cover, the frame being shown in dotted outline. Fig. 2 is a side view of

the cover shown in Fig. 1. Fig. 3 is an enlarged section of one edge of the cover, taken on a plane indicated by the line 3-3 in Fig 1. Fig. 4 is a plan view of a corner 60 of the frame, the metal cover being shown in section on a plane indicated by line 4-4 in Fig. 2. Fig. 5 is an enlarged face view of the blank from which the top member or plate of the cover is made. Fig. 6 is a similar view of the bottom plate, and Fig. 7 is a perspective view of the construction shown in Fig. 6, partly bent up at the sides, this figure being inserted to illustrate the relative position of the parts more clearly. 70

These covers are made according to the size and shape desired, but for the purpose of illustrating the device we show a rectangular cover, this being usually made of a frame-work which is incased in the sheet 75 metal covering, which is usually tin or galvanized iron or other similar material, and in Fig. 1 the frame 10 is illustrated as being rectangular, this frame being usually made of wooden strips heavy enough to act as a support for the plates or sheets that incase 80 the cover, and also to hold up articles of considerable weight when the cover is used as a table.

The frame is provided on the bottom with 85 a bottom plate or sheet 11, which is made of sheet metal and is formed into a blank which has wings 12, these being shown more particularly in Figs. 6 and 7, these wings being 90 bent upward to form the sides of the cover, and they fit against the outside edge of the frame 10. The edge of one wing at each corner is provided with a lip 13 which, when bent up, fits in as shown in Fig. 7 to cover the corner of the frame, and the wing that 95 forms the side that abuts against the lip 13 incases the lip, and in this way the corner seam, as shown in Fig. 4, is tight and it is also strengthened.

The edge 14 on each side of the cover is 100 bent outward, as shown at a in Fig. 7, and the top member or plate 15, which is preferably of sheet metal and which is formed into a blank, one form of which is shown in Fig. 5, is then laid on the frame 10 so that the 105 strips 16 lie on the out-turned edges 14 of the bottom plate, and the edge strips 17 of the top plate are then bent around the edges 14 to embrace these edges and form an interlocked seam which is then crimped down, 110 as shown in Fig. 3, so that the seam 18 lies substantially close to and is parallel with

the sides of the cover and is constructed so as to shed water or other liquid on the top of the cover, and forms a tight joint without soldering, this joint and the corner joint shown in Fig. 4 insuring the protection of the frame from any rotting, does not provide for any projecting points to accidentally catch the hands or the clothing and tightly fits the sheet metal plates over the frame without the use of nails, tacks or other fastening devices.

In order to make the corners of the interlocked seam 18 close fitting, the parts that will abut of the edge strip 17 are cut away, as at 19, so that when folded in, these edges do not extend to the corner and the corners of the strips 16 can be brought close together and tightly fitted, and being of but one thickness of metal, a slight tapping with a mallet or similar tool will cause this part of the corner to be forced together tightly.

The cover can be secured to a suitable support so that it can be swung out of place, the hinges 20 being adapted to be used for this purpose, although other means for fastening the cover can be employed.

We claim:

1. A cover for washtubs and the like comprising a frame, a bottom plate on the frame bent upward against the frame to form the

sides, and a top plate fitting on the frame and with its edges joined to the bottom plate at the top of the sides by an interlocking seam, said seam being crimped to lie parallel with the sides.

2. A cover for washtubs and the like comprising a frame, a bottom plate on the frame and bent to form the sides of the cover, lips on the sides to cover the corners of the frame and to be incased by the adjacent sides, and a top plate, the edges of the top plate and the bottom plate being joined by an interlocking seam crimped downward to lie parallel with and against the tops of the sides of the cover.

3. A cover for washtubs comprising a bottom plate provided with wings forming the sides of the cover, each wing having a lip incased by the next adjacent wing and having an edge strip, and a top plate with an edge strip on each side and joined by an interlocking seam to the edge of the bottom plate crimped downward at the tops of the sides to lie against the sides.

In testimony that we claim the foregoing, we have hereto set our hands, this 18th day of March, 1919.

WILLIAM FADER.
JOE SCHATMAN.
LOUIS GOLDBERG.
